[57] CLAIM

The ornamental design for a flagon, as shown and described.

DESCRIPTION

FIG. 1 is an elevational view of a flagon showing my new design;

FIG. 2 is a top plan view;

FIG. 3 is an elevation view showing the side opposite that seen in FIG. 1; and

FIG. 4 is a bottom plan view.

The drawing is stippled to show contrasting color.

FIG. 1

FIG. 2

FIG. 3

FIG. 4
